UNITED STATES PATENT OFFICE.

EDWARD D. ROCKWELL, OF BRISTOL, CONNECTICUT, ASSIGNOR TO THE LIBERTY BELL COMPANY, OF SAME PLACE.

DESIGN FOR A GONG FOR BELLS.

SPECIFICATION forming part of Design No. 31,888, dated November 28, 1899.

Application filed October 31, 1899. Serial No. 785,427. Term of patent 7 years.

To all whom it may concern:

Be it known that I, EDWARD D. ROCKWELL, a citizen of the United States, and a resident of Bristol, in the county of Hartford and State of Connecticut, have invented and produced a new and original Design for Gongs for Bells, of which the following is a specification, reference being had to the accompanying drawings, forming part thereof.

10 Figure 1 is a plan view of a gong, showing my new design. Fig. 2 is a view in side elevation of the same.

The gong is of the rounded or oval shape common to articles of this class; and the leading or material feature of my design, as shown 15 in the drawings, consists of an endless row of bead-like projections *b*, extending around the gong *a* and inclosing a plain surface *c*, located at or near the top of the gong when viewed in 20 side elevation, as in Fig. 2, and at or near the

center when viewed in plan, as in Fig. 1. This row of bead-like projections forms a boundary-line for the plain surface located within its border.

It is apparent that this design is also applicable to other articles having a rounded surface.

Having described my invention, what I claim as new, and desire to secure by Letters Patent, is—

The design for a gong for a bell, as herein shown and described.

In testimony whereof I have signed my name to this specification in the presence of two subscribing witnesses.

EDWARD D. ROCKWELL.
